[57] CLAIM

The ornamental design for a boat lift control unit, as shown and described.

DESCRIPTION

FIG. 1 is a top, front and left side perspective view of a boat lift control unit showing my new design. The cables are shown broken-away to indicate indeterminate length;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof;

FIG. 8 is a top, front and left side view thereof in open position;

FIG. 9 is a front view thereof;

FIG. 10 is a rear view thereof;

FIG. 11 is a left side view thereof; and,

FIG. 12 is a top plan view thereof.
